UNITED STATES PATENT OFFICE.

ALONZO E. RHOADES, OF HOPEDALE, MASSACHUSETTS, ASSIGNOR TO DRAPER COMPANY, OF PORTLAND, MAINE, AND HOPEDALE, MASSACHUSETTS.

SPINNING-FRAME.

SPECIFICATION forming part of Letters Patent No. 722,145, dated March 3, 1903.

Application filed June 12, 1902. Serial No. 111,334. (No model.)

To all whom it may concern:

Be it known that I, ALONZO E. RHOADES, a citizen of the United States, residing at Hopedale, in the county of Worcester and State of Massachusetts, have invented an Improvement in Spinning-Frames, of which the following description, in connection with the accompanying drawings, is a specification, like characters on the drawings representing like parts.

In United States Patent No. 686,906, dated November 19, 1901, an apparatus is shown and described whereby a spinning-frame is adapted to wind the yarn upon a yarn receiver or bobbin in such manner that a preliminary winding or bunch is first laid and thereafter a main or service winding of yarn is laid, the yarn-receivers so wound being subsequently used in the shuttles of automatic filling-replenishing "feeler-looms," a feeler acting to effect a change of filling when the yarn has been woven off down to the preliminary winding and while there yet remains sufficient yarn to extend one or more times across the loom. Means are provided in said patent for regulating the position of the preliminary winding on the barrel of the yarn-receiver, for varying the length of traverse during the formation of such winding, and for varying the volume or amount of yarn therein. My present invention relates to the same type of apparatus as is disclosed in said patent; and it has for its object the production of various improvements in such apparatus, whereby more convenient adjustments may be made, and I have also made provision herein for adapting my invention to a somewhat different type of spinning-frame, as will more clearly appear herein-after.

In the patent referred to the ring-rail is raised by means of a lifting-weight and depressed by or through the "builder-motion," the drum thereof being gradually unwound to effect the "gain" of the traverse by letting off the chain little by little as the yarn is laid upon the yarn-receiver. Another type of spinning-frame, however, which is extensively used is provided with means whereby the lifting of the ring-rail is effected by the

builder-motion, the descent of the rail being due to gravity, and in such apparatus the drum of the builder-motion gradually winds up the chain in order to effect the gain of the traverse, and my present invention is shown in connection with such latter type of spinning-frame.

Figure 1 is a front elevation of a portion of a spinning-frame showing the builder-motion and coöperating parts embodying my present invention, the preliminary winding or bunch of yarn having been laid on the yarn-receivers or bobbins, the ring-rail being shown at the bottom of such preliminary winding and with the apparatus ready to begin the main or service winding. Fig. 2 is a transverse sectional view on the line 2 2, Fig. 1, looking toward the left, the rocker-arm being omitted. Fig. 3 is an enlarged side elevation of a bobbin, showing the preliminary winding or bunch thereon completed, and the ring-rail at such time is at the lowest point of its traverse and ready to ascend to begin the main winding with the full traverse, the ring being indicated in dotted lines. Fig. 4 is an enlarged front elevation of the carriage, its support, and the means for controlling the traverse to form the preliminary and the main windings, the parts corresponding in position to Figs. 1 and 2. Fig. 5 is a top or plan view thereof, also enlarged. Fig. 6 is a rear side elevation, partly broken out, of the mechanism shown in Fig. 4. Fig. 7 is a transverse section on the line 7 7, Fig. 6, looking toward the right. Fig. 8 is a detached detail in plan of the traverse-controlling means in the relative position shown in Fig. 5. Fig. 9 is a top or plan view of the carriage detached. Fig. 10 is a side elevation of the locking-lever, to be hereinafter described, taken in connection with one member of the means for regulating the volume of the preliminary winding. Fig. 11 is a side elevation, detached, of the unlocking device. Fig. 12 is a similar view of the pawl-carrier and pawl forming a part of the means for regulating the volume of the preliminary winding. Fig. 13 is a side elevation of another member of said regulating means, by the adjustment of which is determined the extent of angular movement of the ratchet.

forming a part of said means; and Fig. 14 is a plan view of the traverse-controlling means for the preliminary winding, taken during such winding.

5 Referring to Figs. 1 and 2, the frame A, spindle-rail R^x , on which are mounted rotatable sleeve-whirl spindles S, the vertically-reciprocating ring-rail R, provided with rings R' , one for each spindle, the lifter-rods L, only one of which is shown, (see Fig. 1,) the rockers L^x , each having a roll, as 3, for the foot of the lifter-rod, and a counterbalancing-weight W, and the upturned rocker-arm L', rigidly connected with each rocker, may be 15 and are all of well-known construction in spinning-frames, the arms L' being connected by a link L² to swing in unison, so that the power applied to one rocker will be transmitted to the other one, and thence through the 20 lifter-rods to the ring-rail.

It is assumed that the rockers are mounted near opposite ends of the frame, and in the apparatus herein shown the descent of the ring-rail is effected by gravity, and its ascent 25 is accomplished positively by or through the builder-motion, and owing to the type of frame herein illustrated I have shown the builder-motion connected with the arm L' of the rocker farthest therefrom. The builder-arm 30 B^x, fulcrumed on the frame at B', is provided with a follower b^x, Fig. 2, to coöperate with an actuating or traverse cam T, herein shown as heart-shaped, said builder-arm having mounted upon it the winding mechanism, including a drum M, pick-shaft m, provided with a worm m^x to effect gradual rotation of the drum, pick-wheel m' on said shaft, and an actuating-pawl m², operated in usual manner, the rotation of the cam rocking the 35 builder-arm to effect through intervening connections the traverse of the ring-rail.

A weight B² on the builder-arm counterbalances the weight of the winding mechanism and maintains the follower b^x in engagement with cam T.

45 From an inspection of Fig. 1 it will be manifest that each depression of the builder-arm will raise the ring-rail, and in order to effect the gain of the traverse, whereby at each 50 upstroke the rail rises a little higher and at each downstroke descends not quite so low as on the previous stroke, laying the yarn upon the bobbin in successive layers from the lower end or base thereof upward, the chain 55 C^x, secured at one end on the drum M and indirectly connected with the ring-rail, must be gradually wound up. The chain C^x leads up over a sheave 5, rotatably mounted on the girder A^x of the main frame, and it is ad- 60 justably connected, by means to be described, with a carriage G, mounted to slide longitudinally on a supporting-bar d, Figs. 5, 6, and 7, rigidly secured to ears d', secured to or 65 forming part of a stand D, mounted on the girder A^x and having a horizontal guideway d^x parallel to the bar d to receive a fin c^x on a lateral extension c of the carriage, the bar

and guideway constituting a track for the latter, substantially as in my patent referred to. The carriage has an offset c', provided with 70 an upturned stud c² and with a horizontal lug or stop c⁷⁵ for a purpose to be described, and an upright hub c³ is made on the extension c, and viewing Fig. 6 the carriage has at its right hand or outer end a depending portion c⁴, provided with a lateral fulcrum-stud e for the locking-lever E. (Shown separately in Fig. 10.) A locking-pin e^x is pivotally connected at e' with the locking-lever and upturned to slide loosely in the hub c³, the pin 80 projecting a considerable distance above the top of said hub when in operative position, as in Fig. 7. The opposite end e² of the lever E is the heavier to normally lift the locking-pin, and a follower-stud e³ projects laterally from said lever on the side nearest the stand D and at the heavier end of the lever.

An unlocking device (shown separately in Fig. 11) is herein shown as a compound lever 90 E' E², both parts being fulcrumed at e⁴ on a depending apron d² of the stand, the fulcrum-stud e⁴ passing through a longitudinal slot d³, Fig. 4, and being clamped in adjusted position by a nut e⁵, substantially as in the 95 patent referred to. The lever member E² has pivoted upon it at e⁶ a switch e⁷, a cam-lug e⁸ on the member E² being upwardly inclined from the pivoted end of the switch, the lower end of the cam-lug forming a stop-shoulder 9 100 to limit downward movement of the switch without interfering with its upward swing on its fulcrum, the structure being clearly shown in Fig. 11, and referring to Figs. 5 and 6 it will be seen that the switch and cam-lug are 105 in the path of the follower-stud e³, and the apron d² is provided on its inner face with an elongated stop d⁴, projecting beneath the switch.

In my prior patent the unlocking device E' 110 E² is made as a single casting; but herein I have shown the members E' E² as separate and pivotally connected, the member E² being forked or bifurcated at its fulcrum, as at e⁸⁰, (see Fig. 5,) to receive between the forks 115 or bifurcations the pivoted end of the member E', the latter having a toe e⁸¹ (see dotted lines, Figs. 5, 6, and 11) to project beneath a shoulder e⁸² on the member E². The weighted end of the member E' maintains the toe and shoulder in engagement and the parts in the relative position shown in Figs. 6 and 11, a projection d⁴⁰ on the apron, Fig. 6, serving to limit the downward movement of the member E'. Manifestly the member E² can be 125 swung upwardly on its fulcrum e⁴ without moving the member E', and downward swing of said member E² will be resisted or controlled by the weight of the member E'.

The locking-lever E moves bodily with the 130 carriage C, while the unlocking-lever E' E² is fulcrumed on a fixed stud e⁴, and, referring to Fig. 6, if the carriage is moving toward the right the follower-stud e³ will pass be-

neath the cam-lug e^9 and the switch e^7 , lifting the point of the latter and permitting it to drop into the position shown in Fig. 6 after the stud has passed, this operation being 5 hereinafter referred to when describing the operation of the apparatus as a whole. The upright stud c^2 at the back of the carriage is loosely extended through a hub f^x of one member F of the traverse-shifting means, 10 (shown separately in Figs. 8 and 14,) said member F being made as a casting, having the hub at one end and an extension f at its opposite end, of reduced thickness, and at one side a depending stop f^2 , adapted to bring up 15 against the nearest ear d' should the connection between the controlling means and the rocker-arm L' be released. Opposite to the stop f^2 the side of the member F is recessed, as at f' , to abut against the upper end of the 20 locking-pin e^x when the parts are in the position shown in Figs. 4 to 7, inclusive. The bottom of the hub f^x rests on the flat top of the offset c' of the carriage, as shown in Fig. 7, so that the member F may at times swing 25 horizontally on the stud c^2 , so that the recess f' may be moved into and out of alignment with the locking-pin.

The member F is provided with a longitudinal rib f^3 on its upper face, embraced by 30 a groove g (see Fig. 4) in the bottom of a slide member G, having a longitudinal slot g^2 therein to receive a clamping-screw g' , which enters a suitable threaded hole in the rib f^3 , so that by means of the clamping-screw the 35 plate G can be held rigidly in adjusted position nearer or farther from the fulcrum c^2 of the member F, a washer g^3 being interposed between the head of the clamping-screw and the top of the member G.

40 A chain or other flexible connection C^{10} , Fig. 1, is attached at one end to the rocker-arm L', and at its other end it is connected with a hook g^4 , pivotally connected by a bolt g^5 with an overhanging part g^6 of the member G.

45 The hub f^x has an ear f^4 at its outer side provided with a tapered hole f^6 to receive the shank of a hook 20, which is attached to the adjacent end of the winding-chain C^x , a collar 21 having a rounded end to abut against the concaved face f^7 of the ear f^4 surrounding the end of the shank, which latter is threaded, and set-nuts 22 are screwed onto the threaded end of the shank, as clearly shown in 50 Figs. 5, 8, and 14.

55 By setting up or easing off the nuts the position of the preliminary winding or bunch on the filling-carrier will be changed, so that if the nuts are set up the ring-rail will be elevated and if the nuts are let off the ring-rail will be lowered slightly, thereby in the one case or the other positioning the bunch or preliminary winding higher up on the bobbin or lower down nearer its head.

60 65 In my prior patent the construction therein is such that an adjustment similar to that just described varied the amount of yarn in

the preliminary winding, and in my present invention I have provided other means for varying the amount of yarn in such winding, 70 and such means will be hereinafter described.

The rounding of the end of the nut 21 permits the hook 20 to swing on the concaved portion f^7 of the hub f^4 as a fulcrum when the member F changes its position from that 75 shown in Fig. 5 to the position shown in Fig. 14, or vice versa.

As the locking member E is mounted on the carriage, it will be manifest that when the locking-pin e^x is raised above the top of the 80 hub c^2 the member F will be held or locked from movement to the right, viewing Fig. 5, relatively to the carriage; but if the locking-pin is depressed below the member F the latter can swing on its fulcrum c^2 to the right, 85 and during the formation of the preliminary winding the member F is unlocked and free to swing on its fulcrum c^2 , and it is automatically locked or held from swinging movement to the right, viewing Fig. 5, at the beginning of the main or service winding, as 90 will be more particularly referred to herein-after.

Referring to Figs. 4 and 5, the stand D is provided with a vertical recess 24, and another 95 vertical recess 23 is formed in a forward extension D^{10} on the stand, the recess 23 receiving a depressor, shown as a slide-bar h vertically movable in the recess 23 and beveled at its upper end at h' , its lower end projecting below the stand and having a transverse slot h^2 , loosely entered by a stud h^3 on a lever H, fulcrumed below the stand at h^x and having its outer end weighted, as at H' . A similar slide-bar k is vertically movable in the recess 24, and 100 its upper end is beveled at k' , while a transverse slot k^2 at its lower end loosely receives a stud k^3 on the lever H, the two arms of the lever H being offset one from the other, as shown in plan view, Fig. 5, and herein the slide-bars h and k are pivotally connected on opposite sides 105 of the right-hand arm of said lever viewing Fig.

4. The free end of the lever is provided with an inturned toe h^4 , which extends beneath the lower edge of the stand D and limits the 110 upward movement of the slide-bars h and k .

A latch h^6 , having a notch h^5 , is fulcrumed on the stand at h^7 , the latch having a weighted offset h^8 , tending to swing the latch to the left against the end of a dog h^{20} (fulcrumed 115 on the stand at h^{21}) during the time that the main winding of yarn is being laid upon the bobbin, such position of the parts being shown in Fig. 4. The dog h^{20} is provided with a 120 depending tail h^{22} , longitudinally slotted at h^{23} to receive loosely a pin h^{24} , extended laterally from the weighted end H' of the lever H. The latch is upturned at the left of its fulcrum, viewing Fig. 4, to form a trip h^9 , 125 which extends above the stand D when the notch h^5 and the dog h^{20} are in engagement, the trip at that time being in the path of the extension f of the member F, the lower face of such part sliding upon the top of the

130

stand. A cam-wing h^{10} is extended from the trip for a purpose to be described.

The part f of the member F of the traverse-regulating device extends across the stand D 5 toward the front of the spinning-frame far enough to include in its longitudinal path of movement the upper beveled edge of the slide-bar k ; but the slide-bar h is outside of or beyond such path of movement, as will be 10 manifest from an inspection of Fig. 5. The upright face of the part f is rounded or convexed, as at f^8 , to rock on the upright flat face of the slide-bar k as a fulcrum during the formation of the preliminary winding, as 15 shown in Fig. 14.

Referring now to Figs. 6, 7, and 10, the carriage C is provided with a hanger c^{70} , on which is rotatably mounted a ratchet r^x , having a sleeve-like hub r' and a reentrant or 20 cut-away part r , so that its toothed periphery is non-continuous. The stud c^{71} , which is rigidly secured to the hanger c^{70} and on which the ratchet r^x is mounted, also supports between the ratchet and the hanger the hub 25 p^x of a pawl-carrier P, (shown separately in Fig. 12,) one end of the pawl-carrier having a beveled toe p and at its opposite end an enlargement or weight p' , and on the end nearest the toe a pawl p^2 is fulcrumed at p^3 , said 30 pawl being shaped to present a tooth p^4 , which overhangs and co-operates with the ratchet r^x , and projections p^5 p^6 on the pawl are arranged to co-operate, respectively, with pins 35 55 and 66 on the carriage C. That one of the ears d' nearer the toe p of the pawl-carrier is provided with a longitudinally-slotted extension d^{17} , (see Fig. 6,) in which is adjustably mounted a roll or other stud d^{18} to co-operate with the toe p and depress it when 40 the carriage is moved to the left, viewing Fig. 6, to thereby lower the pawl into position to cause its tooth p^4 to engage one of the teeth of the ratchet, and when the carriage C thereafter moves to the right, still viewing 45 Fig. 6, the weighted end p' of the pawl-carrier swings the latter to elevate the pawl and at the same time turn the ratchet through a space equal to one tooth, the continued up-swinging of the pawl-carrier bringing it into 50 position (shown in Fig. 6) with the projection p^6 against the stop 66, the function of the pin 55 being to lift the pawl by engaging the projection p^5 , to thereby disengage it from the ratchet. Thus the ratchet will be turned 55 through a small angular distance each time the carriage is moved to the left, Fig. 6, during the winding of the bunch, and the number of teeth through which the ratchet is turned by the means described regulates or 60 controls the number of layers of yarn which will be laid upon the bobbin during the winding of the bunch.

In order to determine how far the ratchet shall be turned in the direction of the arrow 65 90, Figs. 6 and 10, I have mounted upon the hub r' of the ratchet a stop-arm N, having an oppositely-extended and weighted end N' , a

set-screw N^x holding the stop-arm fixedly upon the ratchet-hub r' .

Referring now to Fig. 6, if the ratchet were 70 free to turn on the fulcrum-stud c^{71} , opposite to the arrow 90, (such movement being induced by the eccentrically-located weight N' ,) the stop-arm N would be swung up against the lateral projection c^{75} on the carriage, and such 75 angular movement of the ratchet would carry the reentrant portion r thereof upward from the position shown in Figs. 6 and 10. Then when the carriage began its reciprocations the step-by-step rotation of the ratchet in the 80 direction of the arrow 90, effected by or through the pawl p^2 , would continue until the ratchet arrived at the position shown in Figs. 6 and 10. Consequently a certain number of engagements of the pawl and ratchet must have 85 taken place to turn the ratchet sufficiently to carry the stop-arm N from its upper position against the extension c^{75} down to the position shown in Fig. 6, and by loosening the set-screw N^x and changing the angular position of the arm N relatively to the reentrant part r of the ratchet the latter would have to be turned a greater or a less angular distance before the ratchet would assume the position shown in Fig. 6—that is to say, if the stop-arm were adjusted at a greater distance from the extension c^{75} than is shown in Fig. 6 it will be manifest that the ratchet would have to be turned a greater distance to bring it into the position shown, whereas if the stop-arm 100 were adjusted nearer to the extension c^{75} than shown in the drawings a less rotative movement of the ratchet would be effected.

The locking-lever E has at its end adjacent the locking-pin e^x a depending segmental 105 extension e^{18} , provided at its lower end with a lateral projection or lug e^{19} , constituting a detent and stop for the ratchet, said lug e^{19} acting as a stop when it can enter the reentrant part r , as shown in the drawings, and 110 acting as a detent during the angular movement of the ratchet to bring the reentrant portion thereof opposite to the projection e^{19} , it being remembered that the tendency of the eccentric weight N' is always to turn the 115 ratchet opposite to the direction of the arrow 90, while the weight p' of the pawl-carrier acts to turn the ratchet in the opposite direction, and in order that the pawl may turn the ratchet when it is in engagement therewith 120 the weight p' is heavier than N' .

Referring now to Figs. 4, 5, 7, and 8, the part f of the member F is provided with an upright post f^{20} , on which is fulcrumed at f^{21} a weighted pawl f^{22} , the lower end of the pawl 125 being beveled, as at f^{23} , Fig. 4, to correspond with the bevel h' of the depressor, the latter being located in the path of movement of the pawl as the carriage C is traversed back and forth, the object of the pawl being to act 130 upon the depressor h and move it downward to lock it into position, as will be described.

In Fig. 3 the bobbin or yarn-receiver is shown as of well-known construction and com-

prising a barrel n , having an enlarged head or base n' , the cylindrical portion of the barrel near the head, and which is technically termed the "feeler-wood," as at n^x , indicating the portion of the barrel on which the preliminary winding or bunch of yarn is laid. It is desired to wind upon this bobbin a preliminary winding or bunch, as t , and thereafter to complete the winding by the main or service winding, (indicated by the dotted lines t' ,) and the mechanism hereinafter described is constructed and arranged to automatically wind such bunch and thereafter to lay the main or service winding, both being laid with the filling-winding—that is, the traverse is uniform during the winding of the bunch t , although it is shorter than the traverse with which the main winding t' is laid, the gain of the traverse being provided for to lay the yarn in succeeding superposed layers around the bobbin.

The operation of the apparatus will now be described in detail, beginning with the starting of the main or service winding, inasmuch as the drawings show the parts in position to begin such winding.

Referring now, therefore, more particularly to Figs. 4, 5, and 6 in connection with Figs. 1 and 2, the preliminary winding or bunch t has just been completed. The short traverse has been finished and the locking-pin e^x has risen through the hub c^3 into the recess f' of the member F of the traverse-shifting means, so that said member will move bodily with the carriage C, and the part f of the member F is behind the slide-bar h and adjacent and just to the left of the slide-bar k , Fig. 5. The weight of the ring-rail acting through the chain C^{10} and hook g^4 upon the member F will hold such member pressed against the locking-pin e^x , as the lever-arm between the fulcrum c^2 of the traverse-shifting means and the bolt g^5 is greater than the distance between said fulcrum and the hook 20, attached to the chain C^x . The traverse or actuating cam T rotates in the direction of the arrow 700, Fig. 2, and as it rotates from the position shown therein the builder-arm B^x will be swung downward and will act 45 through the chain C^x to move the carriage C and the parts mounted thereupon to the left, Figs. 4 and 5, in the direction of the arrow 800, or to the right, viewing Fig. 6, and the rockers L^x will be swung up to elevate the ring-rail, 55 the latter starting from the bottom of the bunch or preliminary winding and making its full traverse, effected by the cam T, to the upper end of and slightly above the bunch. As the carriage is moved on its first stroke in 60 the direction of the arrow 800 the pawl f^{22} will ride over the upper beveled end of and depress the slide-bar h , thereby tilting the lever H, raising its weighted end H' , so that the pin h^{24} thereon will act through the tail of the dog h^{20} to depress the dog until the latch h^6 swings over to bring the end of the dog and the notch h^5 into engagement, and at that

time both of the slide-bars h and k will be lowered below or flush with the top of the stand D and so retained while the dog and latch remain in engagement. The next stroke of the carriage C will be to the right, Figs. 4 and 5, and the full length of the long traverse, and its long stroke, communicated to the ring-rail by intermediate connections, will effect 75 the long traverse for laying yarn upon the bobbin in the formation of the main or service winding t' , and the gain of the traverse during such winding is effected by the gradual winding up of the chain C^x on the drum 80 of the winding mechanism carried by the builder-arm. Such gain of the traverse causes the carriage C at each left-hand stroke, viewing Figs. 4 and 5, to move a little farther toward the left and not quite so far 85 to the right on each right-hand stroke, and just before the service-winding is completed this gradual advance of the carriage toward the left, Figs. 4 and 5, will bring the edge of the part f of the member F into contact with the trip h^9 , rocking the latch h^6 and withdrawing its notch from engagement with the dog h^{20} , so that the lever H will by reason of its weighted end H' swing up into the position shown in Fig. 4, elevating the slide-bars h 95 and k , and very shortly after this movement of the slide-bars into the position shown the main winding will be completed.

In the apparatus herein shown, as is usual in spinning-frames, when a bobbin or set of 100 bobbins has been filled it is necessary to wind back by hand, to thereby set the apparatus in readiness to begin the winding of a new set of bobbins, the winding back being effected by throwing out the pawl m^2 and rotating the 105 pick-wheel m' in such a manner that the chain C^x will be unwound from the drum M. Remembering that at the completion of the main winding the carriage C and the parts carried thereby are nearer the left-hand end 110 of the stand D, viewing Figs. 1, 4, and 5, the winding back (which is really an unwinding) will permit the carriage to move bodily to the right, and during such movement the pawl f^{22} will lift over and drop past the upturned 115 end of the slide-bar h , and the rounded corner f^8 of the member F will bring up against the upturned vertical edge of the slide-bar k , thereby assuming the position shown in Figs. 4 and 5. During the formation of the main 120 winding with the long or full traverse the locking-pin e^x has remained in engagement with the member F of the traverse-shifting means, as has been described; but inasmuch as the locking-lever E travels with the carriage the stud e^3 and the locking-lever will have been gradually moved toward the right, viewing Fig. 6, or to the left, Figs. 4 and 5, until the said stud has passed beneath and beyond the point of the switch e^7 , permitting 125 the latter to drop into the position shown in Figs. 6 and 11, so that when the resetting or winding back is effected the stud will contact with and ride over the upper face of

the switch at or about the time that the pawl f^{22} lifts and drops over the slide-bar h . The act of winding back carries the stud e^3 onto the cam-lug e^9 of the lever member E^2 , 5 depressing the latter, and thereby raising the weighted member E' until the stop d^4 is encountered, bringing the member E^2 to a stop, and then the continued movement of the carriage toward the right, Fig. 4, or toward the left, Fig. 6, during winding back acts through the cam-lug e^9 and the stud e^3 to tilt the locking member E to draw the locking-pin e^x down in front of the member F and below its under face. As soon as the locking-pin is thus withdrawn 15 the pull of the chain C^{10} will exert a greater influence on the traverse-shifting means F and G than will the pull in the opposite direction on the carriage C through the chain C^x , and the edge f^8 of the member F will bear against the upright edge of the slide-bar k and act as a fulcrum to swing the rigidly-connected members F G on such fulcrum to move the carriage to the right, viewing Fig. 5, from the position shown therein to 20 about the position shown in Fig. 14, (the limit permitted by winding back,) the pin e^x moving bodily with the carriage, and the fulcrum edge f^8 will remain in contact with the slide-bar k , the latter serving as the fulcrum for 25 the connected members F G during the formation of the preliminary winding or bunch upon the bobbin, and the slide-bar k will be designated as the "fulcrum" member. By referring to Fig. 14 it will be seen that when 30 the parts are shown in that position the pawl f^{22} is diagonally across the beveled upper end of the slide-bar h , and the latter will be slightly depressed, but not enough to lower the slide-bar k from engagement with the fulcrum edge f^8 , and no further depression of bar h can then take place, as the carriage C is at the limit of its movement to the right. The apparatus is now ready to begin the preliminary winding or bunch, and the rotation 35 of the actuating-cam T acts to reciprocate the carriage C with the same stroke heretofore imparted to it; but at this time it will be noted that the members F G swing in unison on the fulcrum member k , and inasmuch as 40 the chain C^{10} is attached to the member G quite near the fulcrum edge f^8 it will be manifest that the long stroke of the carriage will effect a very much shorter stroke for the ring-rail, the length of the short stroke depending 45 on the adjustment of the member G on the member F toward or from its fulcrum c^2 . The nearer the member G is set or adjusted toward the stud c^2 the farther away it will be from the fulcrum member k and the longer 50 will be the stroke of the ring-rail during the preliminary winding, and, conversely, the nearer the member G is set toward the fulcrum member k the shorter will be the ring-rail stroke. The winding mechanism controls 55 the gain of the traverse during the formation of the preliminary winding or bunch, as well as during the formation of

the main winding, and therefore the carriage C will be gradually advanced toward the left, Figs. 1, 4, and 5, during the bunch formation, and this gradual gain of the carriage acts to gradually bring the members F G and the carriage back again from the position shown in Fig. 14 to the relative position shown in Fig. 5, and when the locking-pin e^x is again lifted into locking position, as will be described, the stroke of the hook g^4 will then be equal to the stroke of the carriage C , the parts then being ready to begin the formation of the main or service winding. The extreme right-hand position of the carriage at such time is shown in Figs. 4 and 5, due to the gain of the carriage to the left during bunch-winding. 70 85

Recurring for a moment to Fig. 6, which, it will be remembered, shows the parts in their position just after the finish of the preliminary winding, it will be seen that the detent e^{19} is in the reentrant portion r of the ratchet; but when the locking-pin is lowered by the travel of the stud e^3 over the upper edge of the cam-lug e^9 , as has been described, such rocking of the lever E withdraws the detent from the reentrant portion of the ratchet, leaving the latter free to be turned oppositely 95 to the arrow 90, Fig. 6, by or through the eccentric weight N' , until the stop-arm N engages the stop c^{15} of the carriage. 90

During the formation of the bunch it will be remembered that each movement of the carriage to the left, Fig. 6, operates through the action of the stud d^{18} upon the toe p of the pawl-carrier to effect engagement of the pawl p^2 with the ratchet, and as the carriage returns the ratchet is rotated through a space 105 equal to one of its teeth, the detent e^{19} at such time clicking over its teeth and preventing retrograde rotation of the ratchet when the pawl is disengaged therefrom after each of its feed-strokes. At each stroke of the carriage from the left, Fig. 6, during bunch-winding the ratchet is advanced one tooth in the direction of the arrow 90 until the reentrant portion r is brought opposite to the detent e^{19} , the number of teeth through which 115 the ratchet has been thus advanced depending upon the setting of the stop-arm N , as has been hereinbefore described, and immediately upon the positioning of the reentrant part of the ratchet opposite the detent the 120 weight of the lever E will lift the end thereof, carrying the detent and the locking-pin into position shown in Fig. 6, terminating bunch-winding and positioning the parts for the immediate beginning of the main or service winding, as shown in Figs. 4 and 5. 125

There will be as many layers of yarn laid upon the bobbin during the formation of the preliminary winding as teeth of the ratchet have been engaged by the pawl p^2 , a very 130 convenient and ready means for adjusting or regulating the amount of yarn to be laid in the bunch being thus provided.

As in my prior patent I employ herein but

one actuating or traverse cam to impart a uniform stroke to the carriage, and I am enabled by or through the traverse-shifting means to produce a short and adjustable traverse very much shorter than the traverse due to the shape of the cam T, and I also provide for automatically changing from short to long traverse, the latter corresponding to the stroke of the carriage C and due to the shape of the actuating-cam. The traverse-shifting means herein shown is capable of very fine adjustment, as it will be manifest that the change of position of the member G upon the member F can be not only readily effected, but with great accuracy and delicacy.

The means for determining the amount of yarn to be wound in the preliminary winding or bunch is totally different from the means shown in my prior patent and is capable of a greater range of adjustment and greater accuracy.

Notwithstanding the fact that in my present invention the resetting of the carriage involves an unwinding of the chain C^X from the drum M, I have retained the term "winding back," as that is the technical term employed for so manipulating the winding mechanism carried by the builder-motion that the frame shall be set in condition for beginning the winding of a set of bobbins.

When the carriage is retrograded by the winding back, the right-hand edge of the part f of the member F will engage the upper edge of the cam-wing h¹⁰ should the latch be accidentally set, and will thereby depress the trip h⁹ out of the way to prevent any injury to the parts.

Having described my invention, what I claim, and desire to secure by Letters Patent, is—

1. In a machine of the class described, a builder-motion, controlling means therefor to effect automatically the formation of two successive windings of yarn upon a yarn-receiver, constituting a bunch and a service-winding, and means to adjust the traverse for the formation of the bunch, said means comprising two members adapted to swing in unison about a common fulcrum during the formation of the bunch, one member being slidably mounted on the other to adjust its distance from the common fulcrum, and a device to clamp said members together in adjusted position.

2. In a machine of the class described, a builder-motion, controlling means therefor to effect automatically the formation of two successive windings of yarn upon a yarn-receiver, constituting a bunch and a service-winding, and means to adjust the traverse for the formation of the bunch, said means comprising two members connected respectively with the builder-motion and the ring-rail of the frame and adapted to swing in unison about a common fulcrum during the formation of the bunch, a longitudinal guide-way on one member on which the other mem-

ber is slidably mounted and adjustable toward and from the common fulcrum, and a device to clamp said members together in adjusted position.

3. In a machine of the class described, a reciprocating ring-rail, a builder-motion, controlling means therefor to effect automatically the formation of a preliminary, and a service winding, of yarn upon a yarn-receiver, both with filling-wind, a carriage reciprocated with a constant stroke by the builder-motion, and means to adjust the traverse for the preliminary winding, said means comprising a member pivotally connected with the carriage and adapted to be swung about a fixed fulcrum by reciprocation of the carriage during preliminary winding, a second member movable on said swinging member toward or from the fixed fulcrum and connected with the ring-rail, and a clamping device to retain the latter member in adjusted position on the swinging member, the distance of the adjustable member from the fixed fulcrum determining the length of traverse of the ring-rail for the preliminary winding.

4. In a machine of the class described, a ring-rail, means, including a builder-motion and a carriage reciprocated thereby with a uniform stroke, to effect the traverse of the ring-rail to lay successively a bunch and a service-winding of yarn upon a yarn-receiver, and means to adjust the length of traverse for the formation of the bunch, said means comprising an elongated member pivotally connected with the carriage and swung thereby about a fixed fulcrum during bunch-winding, a slideable member longitudinally movable on the swinging member toward and from the fixed fulcrum thereof, and a device to clamp said members together in relative adjusted position.

5. In a machine of the class described, a ring-rail, a builder-motion, a carriage intermediate and operatively connected with said ring-rail and builder-motion, to be reciprocated with a uniform stroke by the latter and effect vertical reciprocation of the ring-rail, means to automatically change from a short, uniform traverse to a long, uniform traverse after a bunch of yarn has been wound upon a yarn-receiver, to thereby complete the main winding with a long traverse, said means including a member pivotally connected with the carriage and swung by reciprocation thereof about a fixed fulcrum during bunch-winding, and an adjusting device on and directly connecting said member with the connection between the carriage and builder-motion, to govern the position of the bunch upon the yarn-receiver.

6. In a machine of the class described, a ring-rail, a builder-motion, a carriage operatively connected with the ring-rail, a flexible connection between the builder-motion and the carriage, to reciprocate the latter with a uniform stroke, traverse-shifting means to automatically change from a short, uniform

traverse to a long, uniform traverse, to successively lay a preliminary winding and a main winding of yarn upon a yarn-receiver, said means including a member pivotally connected with the carriage and swung thereby about a fixed fulcrum during preliminary winding, a holding device on said member for and to which is directly attached one end of the flexible connection between the carriage and builder-motion, and means to adjust said holding device on the pivoted member to determine the position of the preliminary winding upon the yarn-receiver.

7. In a machine of the class described, a builder-motion, controlling means to effect automatically the formation of a preliminary winding of yarn upon a yarn-receiver, and thereafter a service-winding, said means including a carriage reciprocated with a uniform stroke, and a member swung thereby about a fixed fulcrum during the formation of the preliminary winding, and devices carried by said member to severally vary the position of the preliminary winding upon the yarn-receiver and to adjust the traverse for such preliminary winding, the traverse-adjusting device being slidably mounted on the swinging member, and movable toward and from its extremity.

8. In a machine of the class described, a builder-motion, controlling means to effect automatically the formation of a preliminary winding of yarn upon a yarn-receiver, and thereafter a service-winding, said means including a carriage reciprocated with a uniform stroke, and a member swung thereby about a fixed fulcrum during the formation of the preliminary winding, and independently-adjustable devices carried by said member adjacent its opposite ends to respectively predetermine the position of the preliminary winding upon the yarn-receiver and to regulate the length of the traverse for such winding, the latter of said devices being slidably mounted on said member at the end nearer the fixed fulcrum.

9. In a machine of the class described, a rotatable spindle, a yarn-receiver thereon, a builder-motion, a filling-wind-actuating device therefor, means to automatically change from a short, uniform traverse to a long, uniform traverse after a bunch of yarn has been wound upon the yarn-receiver, to complete the main winding of yarn with the long traverse, said means including a member adapted to be swung about a fixed fulcrum during the winding of the bunch, and independent, adjustable devices mounted on said member adjacent its opposite ends to govern the position of the bunch upon the yarn-receiver and to determine the length of the short traverse, the latter of said devices being slidably mounted on said member at the end nearer the fixed fulcrum.

10. In a machine of the class described, a rotatable spindle, a yarn-receiver thereon, a builder-motion, a filling-wind-actuating de-

vice therefor, means to automatically change from a short, uniform traverse to a long, uniform traverse after a bunch of yarn has been wound upon the yarn-receiver, to complete the main winding of yarn with the long traverse, said means including a member adapted to be swung about a fixed fulcrum during the winding of the bunch, an adjustable device mounted on said member to govern the position of the bunch upon the yarn-receiver, and means mounted independently of said member to govern the volume of the bunch.

11. In a machine of the class described, a rotatable spindle, a yarn-receiver thereon, a builder-motion, a filling-wind-actuating device therefor, means to automatically change from a short, uniform traverse to a long, uniform traverse after a bunch of yarn has been wound upon the yarn-receiver, to complete the main winding of yarn with the long traverse, said means including a member adapted to be swung about a fixed fulcrum during the winding of the bunch, a device adjustable on said member relative to its fixed fulcrum to determine the length of the short traverse, and means mounted independently of said member to govern the volume of the bunch.

12. In a machine of the class described, a rotatable spindle, a yarn-receiver thereon, a builder-motion, a filling-wind-actuating device therefor, means to automatically change from a short, uniform traverse to a long, uniform traverse after a bunch of yarn has been wound upon the yarn-receiver, to complete the main winding of yarn with the long traverse, said means including a member adapted to be swung about a fixed fulcrum during the winding of the bunch, independently-adjustable devices mounted on said member to severally govern the position of the bunch upon the yarn-receiver and determine the length of the short traverse, and separate means to govern the volume of the said bunch.

13. In a machine of the class described, a reciprocating ring-rail, a builder-motion, a carriage reciprocated thereby with a constant stroke, a winding mechanism, a chain connecting it with the carriage, connections between the latter and the ring-rail, to elevate the rail positively, said winding mechanism automatically taking up the chain to effect the "gain" of the traverse, a traverse-shifter forming a part of the connections between the carriage and ring-rail, to change from a short, uniform traverse to a long, uniform traverse, and means to automatically govern said traverse-shifter in changing from one to the other traverse.

14. In a machine of the class described, a ring-rail, a builder-motion, connections between it and the ring-rail, to reciprocate the latter, said connections including a carriage reciprocated with a constant stroke, and a traverse-shifter to transform the stroke of the carriage to a shorter stroke during the formation of a preliminary winding of yarn upon a yarn-receiver, and thereafter to shift to the

longer carriage stroke to complete the main or service winding; means to govern the volume of the preliminary winding, said means including a rotatable member, a device to rotate it step by step during preliminary winding, the total angular movement of said member determining the number of layers of yarn to be laid in such winding, and an adjustable regulator to predetermine such angular movement; and means rendered operative by or through said rotatable member upon termination of its angular movement to cause the traverse-shifter to shift from short to long stroke.

15 15. In a machine of the class described, a reciprocating ring-rail, means to effect its traverse, including a carriage reciprocated with a constant stroke, a traverse-shifter actuated thereby and interposed between the carriage and the ring-rail, to effect a short, uniform traverse thereof to wind a bunch of yarn upon a yarn-receiver, and thereafter to effect a long, uniform traverse to complete the main or service winding of the yarn; means to govern the volume of the bunch, said means including a mutilated ratchet, a pawl to rotate it step by step during bunch-winding, a detent-stop to coöperate with the ratchet, and a device to predetermine the extent of rotative movement of the ratchet and thereby the number of layers of yarn in the bunch; and a controlling device for the traverse-shifter, rendered operative by or through the detent-stop when coöperating with the mutilated portion of the ratchet, to shift from bunch to main winding.

16. In a machine of the class described, a reciprocating ring-rail; a builder-motion; a carriage reciprocated thereby with a constant stroke; a connection between carriage and ring-rail, to reciprocate the latter, said connection including a traverse-shifter mounted on the carriage and swung by reciprocation thereof about a fixed fulcrum during the formation of a preliminary winding of yarn upon a yarn-receiver; a locking device to prevent relative movement of carriage and traverse-shifter during the formation of the main winding, and means to determine the volume of the preliminary winding, said means including a device independent of the swinging traverse-shifter, to positively retain the locking device inoperative until such volume has been attained.

55 17. In a machine of the class described, a reciprocating ring-rail; a builder-motion; a carriage reciprocated thereby with a constant stroke; a connection between carriage and ring-rail, to reciprocate the latter, said connection including a traverse-shifter mounted on the carriage and swung by reciprocation thereof about a fixed fulcrum during the formation of a preliminary winding of yarn upon a yarn-receiver; a locking device to prevent relative movement of carriage and traverse-shifter during the formation of the main winding, and means to determine the volume

of the preliminary winding, said means including a rotatable member having a re-entrant portion, a detent operatively connected with the locking device and maintaining it inoperative until said detent can enter the reentrant portion, and a regulating device to determine the extent of angular movement of the rotatable member necessary to permit movement of the detent into the reentrant portion.

18. In a machine of the class described, a reciprocating ring-rail; a builder-motion; a carriage reciprocated thereby with a constant stroke; a connection between carriage and ring-rail, to reciprocate the latter, said connection including a traverse-shifter mounted on the carriage and swung by reciprocation thereof about a fixed fulcrum during the formation of a preliminary winding of yarn upon a yarn-receiver; a locking device to prevent relative movement of carriage and traverse-shifter during the formation of the main winding, adjustable means to predetermine the volume of the preliminary winding, including a detent operatively connected with the locking device and a device to automatically release the detent when the preliminary winding has arrived at the predetermined volume; and separate means to automatically actuate the locking device to release the traverse-shifter after the completion of the main winding and prior to beginning a new preliminary winding.

19. In a machine of the class described, a reciprocating ring-rail, a carriage, a traverse-shifter pivotally mounted thereon, connections between the free end of the shifter and the ring-rail, means to reciprocate the carriage with a uniform stroke and to gradually advance it, a fulcrum member about which the shifter swings during a predetermined reciprocation of the carriage, to impart a short traverse to the ring-rail, means operative by or through the carriage to render the fulcrum member inoperative upon completion of the period of short traverse, a locking device to prevent relative movement of carriage and shifter at the end of short traverse, whereby subsequent movement of the carriage imparts a long traverse to the ring-rail, adjustable means to positively engage and maintain the locking device inoperative until a predetermined volume of yarn has been laid upon a yarn-receiver with the short traverse and to thereupon release the locking device, and separate means to unlock the carriage and shifter when the long-traverse period has been completed, the locking device at such time being automatically returned to the control of said adjustable means.

20. In a machine of the class described, a reciprocating ring-rail, a carriage, a traverse-shifter pivotally mounted thereon, connections between the free end of the shifter and the ring-rail, means to reciprocate the carriage with a uniform stroke and to gradually advance it, a fulcrum member about which

- the shifter swings during a predetermined reciprocation of the carriage, to impart a short traverse to the ring-rail, means operative by or through the carriage to render the fulcrum member inoperative upon completion of the period of short traverse, a locking device to prevent relative movement of carriage and shifter at the end of short traverse, whereby subsequent movement of the carriage imparts a long traverse to the ring-rail, and means to determine when the short-traverse period shall end, said means including a ratchet having a recess in its periphery, a pawl to rotate it step by step during short traverse, a detent connected with the locking device and acted upon by the ratchet to maintain said device inoperative until the detent can enter the recess, and a regulating device to determine the extent of rotation of the ratchet before the recess therein is brought opposite the detent, the locking device when so released causing the shifter and carriage to move together and impart a long traverse to the ring-rail.
21. In a machine of the class described, a reciprocating ring-rail, a carriage, a traverse-shifter pivotally mounted thereon, connections between the free end of the shifter and the ring-rail, means to reciprocate the carriage with a uniform stroke and to gradually advance it, a fulcrum member about which the shifter swings during a predetermined reciprocation of the carriage, to impart a short traverse to the ring-rail, means operative by or through the carriage to render the fulcrum member inoperative upon completion of the period of short traverse, a locking device to prevent relative movement of carriage and shifter at the end of short traverse, whereby subsequent movement of the carriage imparts a long traverse to the ring-rail, and means to determine when the short-traverse period shall end, said means including a ratchet having a recess in its periphery, a pawl to rotate it step by step during short traverse, a detent connected with the locking device and acted upon by the ratchet to maintain said device inoperative until the detent can enter the recess, a regulating device to determine the extent of rotation of the ratchet before the recess therein is brought opposite the detent, the locking device when so released causing the shifter and carriage to move together and impart a long traverse to the ring-rail.
22. In a machine of the class described, a reciprocating ring-rail, a carriage, a traverse-shifter pivotally mounted thereon, connections between the free end of the shifter and the ring-rail, means to reciprocate the carriage with a uniform stroke and to gradually advance it, a fulcrum member about which the shifter swings during a predetermined reciprocation of the carriage, to impart a short

traverse to the ring-rail, means operative by or through the carriage to render the fulcrum member inoperative upon completion of the period of short traverse, a locking device to prevent relative movement of carriage and shifter at the end of short traverse, whereby subsequent movement of the carriage imparts a long traverse to the ring-rail, and means to determine when the short-traverse period shall end, said means including a ratchet having a recess in its periphery, a pawl to rotate it step by step during short traverse, a detent connected with the locking device and acted upon by the ratchet to maintain said device inoperative until the detent can enter the recess, a regulating device to determine the extent of rotation of the ratchet before the recess therein is brought opposite the detent, the locking device when so released causing the shifter and carriage to move together and impart a long traverse to the ring-rail, separate means to render the locking device inoperative and thereby unlock the shifter and carriage when the long-traverse period has been completed, the detent being simultaneously withdrawn from the recess of the ratchet, and a device to automatically reset the released ratchet in position to begin its step-by-step rotation when the next preliminary winding is begun.

23. In a machine of the class described, a ring-rail, a builder-motion, including mechanism to govern the "gain" of the traverse, connections between the builder-motion and the ring-rail, said connections including a carriage reciprocated with a uniform stroke, a traverse-shifter pivoted at one end on the carriage, means to automatically lock and unlock the carriage and shifter at predetermined times, a fulcrum member to engage and form a fixed fulcrum for the free end of the shifter, to thereby impart a short traverse to the ring-rail when shifter and carriage are unlocked, means operated by the carriage at the termination of the short-traverse period to render the fulcrum member inoperative, the shifter being at such time locked to the carriage, to impart a long traverse to the ring-rail while they are so locked, and adjustable means independent of the traverse-shifter to positively prevent locking during, and to permit locking at the termination of, the short-traverse period, the adjustment of such means determining the relative volumes of yarn laid upon a yarn-receiver with the short and long traverse respectively.

24. In a machine of the class described, a builder-motion, and controlling means therefor to effect automatically the formation of a bunch, and thereafter a main winding, of yarn upon a yarn-receiver, said means including a reciprocating carriage, a traverse-shifter fulcrumed thereon at one end, an intermittently-operative fixed fulcrum for the other end of said shifter, a locking device to lock the shifter to the carriage when the fixed fulcrum is inoperative, the bunch being formed when

the shifter is rocked on the fixed fulcrum and the main winding when the latter is inoperative, adjustable means to act upon and retain the locking device inoperative during formation of the bunch, the adjustment of said means determining the volume of the bunch, and a device to automatically reset said adjustable means after completion of the main winding and prior to the beginning of a new bunch.

25. In a machine of the class described, a builder-motion, and controlling means therefor to effect automatically the formation of a bunch, and thereafter a main winding, of 10 yarn upon a yarn-receiver, said means including a reciprocating carriage, a traverse-shifter fulcrummed thereon at one end, an intermittently-operative fixed fulcrum for the other end of said shifter, a locking device to 15 lock the shifter to the carriage when the fixed fulcrum is inoperative, the bunch being

formed when the shifter is rocked on the fixed fulcrum, and the main winding when the latter is inoperative, adjustable means to act upon and retain the locking device inoperative 25 during formation of the bunch, the adjustment of said means determining the volume of the bunch, a device to automatically reset said adjustable means after completion of the main winding and prior to the beginning 30 of a new bunch, and independent means to automatically unlock the shifter by or through movement of the carriage when wound back.

In testimony whereof I have signed my 35 name to this specification in the presence of two subscribing witnesses.
